ATTORNEYS

UNITED STATES PATENT OFFICE.

GEORGE KOETTER, OF HOBOKEN, NEW JERSEY.

NONSLIPPING SHOE PAD.

Application filed May 24, 1922. Serial No. 563,236.

To all whom it may concern:

Be it known that I, GEORGE KOETTER, a citizen of the Republic of Germany, and resident of Hoboken, in the county of Hudson and State of New Jersey, have invented certain new and useful Improvements in Non-slipping Shoe Pads, of which the following is a specification.

It is a well known fact that in various athletic sports and games, such as for example bowling, which are played indoors upon hardwood or other slippery floors that considerable difficulty is experienced by the players because of the great slipping tendency of the ordinary leather soled shoes. Because of this fact, it is a common practice for players to provide themselves with a special pair of shoes which are usually provided with corrugated rubber soles, to prevent undue slipping and the accidental falls which may result therefrom. The provision of an extra pair of shoes is an added expense and in addition involves the trouble of carrying a more or less burdensome package as well as the inconvenience of changing from one pair of shoes to another.

The principal object of this invention therefore is to obviate the difficulties hereinbefore enumerated by providing a small non-slipping pad which can be manufactured and sold at a slight cost, which can be readily attached or detached from the ordinary leather street shoe in a few seconds, and which when removed therefrom can be folded into a small compact package adapted to be readily carried in a pocket of the user's apparel.

For the accomplishment of these and such further objects as will hereinafter be apparent to those skilled in the art to which this appertains, the invention consists in the construction, combination and arrangement of parts herein specifically described and illustrated in the accompanying drawings, wherein is shown a preferred embodiment of the invention, but it is to be understood that changes, variations and modifications may be resorted to which fall within the scope of the claims hereunto appended.

In the drawings forming a portion of this specification—

Fig. 1 is a perspective view of a shoe showing a pad embodying my invention attached thereto.

Fig. 2 is a top view of the pad removed from the shoe.

Fig. 3 is a bottom view of the structure shown in Fig. 2.

Fig. 4 is a view similar to Fig. 1 showing a modification.

As shown in the drawings, the improved pad comprises a sole portion 10 which is provided with a plurality of perforations 11 which obviously may be of any suitable size or shape or any number but which preferably are of the form of elongated slots as shown. 65

The perforations preferably extend from a point adjacent the front of the sole to a point slightly to the rear of the ball of the foot. The sole portion as will be seen in Fig. 3 is thereby provided with a strap portion 12 70 which extends across the narrow portion of the shoe at the instep, which strap portion is in effect extended around and across the upper portion of the shoe, as shown at 13, to form a clamping band which effectively prevents the pad from slipping off the shoe. Extending forwardly from the central portion of the part 13 is a toe strap 14 which passes around the toe of the shoe and is joined to the sole or bottom portion 10. 80

Means may be provided in addition to the clamping band to prevent the pad from slipping off when in use and may comprise a lace 15 which is passed through the eyelets 16 provided in the portion 13 and is then brought 85 backwardly around the ankle and forwardly around the arch of the shoe or foot where the ends of the lace are secured or tied together in any suitable manner.

Instead of the lace 15 a piece of elastic 90 webbing 17 may be suitably secured to the portion 13 as by the stitching 18. The free end of the webbing may be provided with any desirable securing means such as the hook 19 adapted to be engaged with the shoe laces 20. It will be understood that the elastic webbing will be stretched so that there will be sufficient tension therein to hold the hook securely in engagement with the laces 20 when the same is engaged therewith, 100 whereby the pad will be held securely in place.

The manner of operation and use of the device will be obvious, it being understood that the device will preferably be constructed of rubber of sufficient elasticity to hold the pad securely in place by means of the clamping band engaging the shoe at the narrow or instep portion. The pad may be constructed of a single piece of rubber or 110

the sole and upper portions may be of separate pieces vulcanized or otherwise joined together. It will, of course be understood that while rubber is preferred for the sole portion, that it may be of any suitable material such as cork, felt or canvas, which has a relatively high coefficient of friction with wood, stone or composition flooring, and that when such materials as cork, felt or canvas are used for the sole portion that the clamping band 13 will be constructed of elastic material such as rubber or elastic webbing. The perforations 11 not only serve to provide a better gripping surface but also in combination with the open spaces between the toe strap and the sole portion permit free ventilation and prevent the objectionable heating and drawing effect which would otherwise be present if the device were constructed entirely of rubber and completely encased the front portion of the shoe.

Having thus described my invention, what I claim as new and desire to secure by Letters Patent, is:—

1. A detachable nonslipping shoe pad comprising a sole portion provided with a plurality of longitudinally extending slots to form a plurality of gripping edges and constructed of material having a high coefficient of friction upon wood, stone or a composition flooring, and a top portion comprising a narrow resilient clamping band, and a toe strap extending from said clamping band to said sole portion, said sole portion having a narrowed rear portion adapted to be held by said clamping band securely in engagement with a nar-

rowed instep portion of the shoe and constructed and arranged on a substantially plane surface, whereby when said top portion is folded down upon said sole portion, the shoe pad will form a substantially flat compact package adapted to be readily carried in a pocket of the user's apparel, and means attached to said clamping band adapted to be detachably engaged with the upper portion of the shoe to hold said pad securely in position upon the shoe.

2. A detachable nonslipping shoe pad comprising a sole portion provided with a plurality of longitudinally extending slots to form a plurality of gripping edges and constructed of material having a high coefficient of friction upon wood, stone or a composition flooring, and a top portion comprising a narrow resilient clamping band, and a toe strap extending from said clamping band to said sole portion, said sole portion having a narrowed rear portion adapted to be held by said clamping band securely in engagement with a narrowed instep portion of the shoe and constructed and arranged on a substantially plane surface, whereby when said top portion is folded down upon said sole portion, the shoe pad will form a substantially flat compact package adapted to be readily carried in a pocket of the user's apparel, and an elastic strip connected with said clamping band provided with means to engage the laces of the shoe.

Signed at New York, in the county of New York and State of New York, this 20 day of May, A. D. 1922.

GEORGE KOETTER.
